FLUID PUMP

Bertram P. Pond, Longmeadow, and Edwin E. Vincent and Warren H. De Lancey, Springfield, Mass., assignors to Engineering Products, Inc., Springfield, Mass., a corporation of Massachusetts

Application January 10, 1947, Serial No. 721,227

1 Claim. (Cl. 103—126)

1

This invention relates to an improved pumping unit, and more particularly to a pumping unit which is designed for use in oil burners.

It is the primary object of the present invention to provide a pumping unit which will be most economical to manufacture but which at the same time will be constructed in a manner such that it may function most efficiently.

A further object of the present invention is to provide a pump unit which will have its component parts so disposed that they may be readily disassembled and reassembled thereby to facilitate the inspection and repair thereof.

With the above and other objects in view, as will hereinafter appear, the invention comprises the devices, combinations and arrangements of parts, hereinafter set forth and illustrated in the accompanying drawings of a preferred embodiment of the invention from which the several features of the invention and the advantages attained thereby will readily be understood by those skilled in the art.

In the accompanying drawings:

Fig. 1 represents a longitudinal sectional view of the present pumping unit.

Fig. 2 is an enlarged sectional view of the valve unit taken substantially along the line 2—2 of Fig. 1.

Fig. 3 is a sectional view through the forward portion of the pumping unit taken substantially along the line 3—3 of Fig. 1.

Fig. 4 represents a sectional view taken substantially along the line 4—4 of Fig. 1.

Fig. 5 represents a sectional view taken substantially along the line 5—5 of Fig. 1.

Fig. 6 represents a sectional view taken substantially along line 6—6 of Fig. 1.

Referring particularly to Fig. 1, the present pumping unit broadly comprises a substantially cylindrical casing 10 having a hollow front chamber 11 formed in the forward portion thereof, which chamber is adapted to be completely enclosed by means of an end cap 12 removably secured to the casing by means of a plurality of bolts 13. Communicating with the chamber 11 is a bore 14 which extends into a rear chamber 15 which in turn opens out upon the rear end portion of the casing 10 to be covered by means of a rear end cap 16 which is removably secured to the casing by means of a plurality of bolts 17. Force fitted into the bore 14 is a hollow sleeve bushing 18 in which is rotatably mounted a driving shaft 19 the distal end portion of which extends through an aperture 20 provided in the end cap 16. An electric motor, or any other suitable prime mover, may be coupled to the dis-

tal end of the shaft 19 for the purpose of rotating the same thereby to actuate the pumping unit. The rearward end of the sleeve 18 is provided with an angular flange 21 which abuts against a rear wall 22 of the chamber 15 and the forward end of this sleeve projects into the chamber 11 and has a back plate 23 of the pumping unit positioned thereabout. Abutting against this back plate 23 within the chamber 11 is an annular ring 24 which forms a spacer unit for the pump proper and abutting against this spacer ring is the front plate 25 of the pumping unit. The two plates 23 and 25 and the spacer ring 24 are all adapted to be secured together by means of a plurality of bolts 26 which are threaded directly into the rear wall portion of the chamber 11.

In order to prevent the shaft 19 from moving endwise within the sleeve 18 an intermediate portion of the shaft has mounted thereon a sealing and thrusting ring 27 the front portion of which abuts against the flange 21 of the sleeve 18 and has an oil slot 27' formed therein. The element 27 cooperates with an annular ring 28 in preventing endwise movements of the shaft and the ring 28 is carried upon the forward end of the shaft 19 and is held thereon by means of a snap ring 29 which may be seated in an annular groove 29' formed on the extreme forward portion of the shaft 19. It is to be understood that the ring 28 abuts against a recessed face 30 of the front plate 25 of the pumping unit.

Referring particularly to Figs. 1 and 3, there is removably positioned in the chamber 11 an oil filter unit comprising a wire screen 31 which is formed substantially into a hollow cylindrical unit which is closed at its ends by means of a forward plate 32 and a rear plate 33. The rear plate 33 is provided with an apertured flanged portion 34 which is adapted to be inserted directly within the recess 30 of the front plate 25 of the pumping unit. It is to be understood that this filter unit, comprising the screen 31 and the front and back plates 32 and 33, may be readily inserted into and removed from the chamber 11 by merely removing the forward cap from the casing 10. Referring particularly to Fig. 1, the front cap 12 has its rear face recessed as at 36 thereby to provide a seat for a coil spring 37 which is adapted to bias the filter unit inwardly so that the flange 34 forcibly engages the edge portions of the recess 30. From the above, it is to be understood that whenever the end cap 12 is removed from the casing 10 the filter unit may be removed from the chamber 11 without disturbing any of the elements of the pumping unit. This is an important

feature of the present device as it permits the filter to be removed and cleaned by unskilled persons.

Referring particularly to Figs. 1 and 5, the present pumping unit is adapted to receive oil from a supply source, not shown herein, and which oil may gain entrance into the pumping unit through a bore 38 provided within the raised portion 39 of the casing 10. An entrance oil line may be secured to either end of the bore 38 while the other end of the bore may be provided with a plug. The oil from the supply source once directed into the bore 38 will find its way into the hollow chamber 11 and about the filter screen 31 through which it will penetrate thus to gain entrance into the filter unit from which it may be then directed into the pumping unit proper.

Referring particularly to Figs. 1, 3, and 4, the recessed face 30 of the front plate 25 is provided with an aperture 48 which is adapted to lead the oil from the inside portion of the filter unit to an arcuately shaped recess 41 provided on the inside face of the plate 25. Referring to Figs. 1 and 5, the oil which gains entrance into the groove 41 will be led directly into a low pressure side of the pumping unit proper which comprises a gear 42 which is mounted directly upon a crowned portion 43 of the shaft 19. A key 44 projecting inwardly from the gear engages the shaft 19 thereby to permit the gear 42 to be driven directly by the shaft. Surrounding the gear 42 is a complementary internal gear 45 which is mounted within an aperture 46 eccentrically provided within the spacer ring 24. As may be seen particularly in Fig. 5, the gear 42 meshes with the internal gear 45 at a point 47 thereby to provide low pressure spaces 48 at the left hand side of the gear and high pressure spaces 49 on the right hand side of the gear. As the shaft 19 rotates in a clockwise direction, as viewed in Fig. 5, the co-acting gears 42 and 45 will create a low pressure within the spaces 48 thereby to draw the oil, provided from the above noted source of supply, into the spaces 48 and to force the same into the spaces 49 from which the oil is directed into an arcuate groove 50, provided in the back face of the forward plate 25 and into an arcuate groove 51 provided in the forward face of the back plate 23 (see Figs. 4 and 6). This oil which gains entrance under pressure into the arcuate grooves 50 and 51 is then forced into a conduit 52 which communicates with the groove 51 and which extends through the back plate 23 to open into a circular recess 53 provided in the rear face of a back plate 23. From this recess 53 the oil, still under pressure, is directed into a longitudinal bore 54 (see Fig. 1) which communicates directly with a second bore 55 which, along with bore 54, is provided in the back wall of the chamber 11. From the above it is to be understood that the pumping unit is adapted to create a low pressure area to which oil from a source of supply is drawn, which oil is passed through the filter unit before gaining entrance into the pumping unit proper. Once within the pumping unit proper, the oil is forced under pressure from the pumping unit and through conduits which lead directly to a valve unit hereinafter to be described.

It is desirable to have some of the oil under high pressure work its way from the pumping unit proper along a spiral oil groove 19' formed in the shaft 19, thus to lubricate the rotating shaft. However, after the oil has thus lubricated the shaft it is to be desired that this oil should be led back into the pump proper rather than having

it spill out along the distal end of the shaft 19. In order to accomplish this purpose there is provided within the chamber 15 of the casing 10 a bellows type sealing unit which comprises a plate 56 which is secured directly between the rear portion of the casing 10 and the rear end cap 16 as at 57. Spaced from the plate 56 and about the shaft 19 is ring 58 connected to the plate 56 by means of cylindrical bellows 59. A coil spring 56, positioned between the ring 58 and the plate 56, functions to bias the ring 58 directly against the ring 27 for the purpose of forming a seal between the rotating ring 27 and the stationary plate 56. The oil which escapes from the pump along the shaft 19 will enter into the chamber 15 and about the bellows 59 by way of the slot 27' formed in the ring 27. This oil in chamber 15 will then enter into a longitudinal bore 61 formed in the casing adjacent the sleeve 18. This bore 61 is in communication with an aperture 62 provided in the back plate 23 of the pump unit which aperture 62 is directed through the plate 23 to open directly within an arcuate slot 63 provided in the forward face of the back plate 23 and disposed in registration with the arcuate slot 41 provided in the rear face of the forward plate 25. Thus, this slot 63 will be positioned adjacent the low pressure areas 48 and, therefore, it will be effective to permit the pumping unit to scavenge the oil from the chamber 15 of the casing 10. This oil will, of course, be recirculated into the system and will finally be directed under pressure into the bore 55.

The above noted valve mechanism of the present device functions as an oil discharge control mechanism to the end that oil cannot be ejected from the pumping unit until or unless the oil reaches a predetermined pressure. Therefore, whenever the pumping unit is first started this valve mechanism is effective to prevent any oil discharge until the pump speed is sufficient to produce a predetermined pressure in the oil. Also this valve will function to cut off the ejection of oil from the pump whenever the pump slows down preparatory to stopping for when the pump slows down it cannot produce a proper pressure of the oil.

Referring particularly to Figs. 1 and 2, this valve unit is provided within a casing protuberance 64 in which is formed a central bore 65 terminating in enlarged end bores 66 and 67. Fixed within the bore 65 is a hollow cylinder 68 in which is slidably received a piston member 69 having a head member 70. Formed within the head member 70 is a longitudinal aperture 71 into which is slidably mounted a needle valve 72 which is surrounded with a coil spring 73 for the purpose of providing a substantially floating mounting for the valve 72. The one end of this spring 73 engages a flange portion 74 of the valve and the other end portion of the spring 73 engages a washer 75 which is held within the head 70 by means of a snap ring 76. Thus the valve 72 is held within the head 70 as a floating element.

Threaded within the bore 66 is a discharge nut 77 having an aperture 78 formed centrally thereof into which is secured a valve seat 79 having a discharge orifice 80 formed axially thereof. This orifice 80 communicates directly with a threaded aperture 81 which is adapted to be connected directly with an oil burner unit. Positioned between the nut 77 and a flange 82, formed on the cylinder 68, is a coil spring 83 the function of which is to secure the sleeve 68 in its proper position at all times.

Threaded into the bore 67 is an adjusting nut 84 which has threaded longitudinally therein an adjusting screw 85 the inner end portion of which has mounted thereon a cap 86 against which one end of a coil spring 87 abuts. The other end of this coil spring 87 projects into the piston 69 to engage the head portion 70 thereof for the purpose of forcing the needle valve 72 into the valve seat 79 thereby to close off the orifice 80. The adjusting screw 85 is provided with the usual screw driver slot 88 which functions to permit the screw to be advanced into or be retracted from the nut 84 thereby to adjust the tension of the spring 87. An acorn nut 89 is threaded over an extended end portion of the nut 84 thereby to prevent fluid leakage at this point.

The hereinabove noted conduit 55 communicates directly with the bore 66 thereby to conduct the oil under pressure from the pumping unit to the bore 66 and about the needle valve 72. It is to be understood that whenever the pressure of this oil reaches a predetermined magnitude it will be sufficient to force the piston 69 against the spring 87 to the end that the valve 72 will be backed away from the valve seat 79 thereby to permit the oil to be ejected through the orifice 80 and to an oil burner unit. By adjusting the screw 85 one may have the valve 72 operate at any given predetermined oil pressure.

Formed in the wall of the cylinder 68, adjacent its flange 82 are a plurality of circumferentially spaced apertures 90 which communicate with the bore 66 and which normally have their inner ends closed off by the piston 69. However, whenever the piston is forced inwardly within the cylinder 68 the apertures 90 will then be placed in register with a plurality of apertures 91 formed within and about the periphery of the piston 69. Whenever the conduits 90 and 91 are thus in register, the oil under pressure will be directed into the hollow portion of the piston 69 from which it will flow through an opening 92 which leads directly into a bore 93 formed within the protuberance 64 (see Figs. 2 and 4). Referring particularly to Fig. 4, one end portion of the bore 93 opens directly within a chamber 11 thus to return the oil back into the pumping system. The lower end of the bore 93 is threaded as at 94 for the purpose of receiving a plug, or if desired a return pipe the other end of which will be connected to the oil supply tank. Thus, it is to be understood that the present pumping unit is adapted to supply oil in excess to the valve orifice 80 and whenever the pressure of this oil is great enough to open the needle valve 72 a portion of this oil will be ejected through the orifice 80 while the remaining oil will be directed back into the pumping system by means of conduits 90 and 91 and the bore 93.

Referring particularly to Figs. 2 and 4, there is provided within the protuberance 64 a second bore 95 which communicates with the bore 66 by means of an opening 96. This bore 95 will receive the high pressure oil directly from the bore 66 and it may have secured to its threaded portion, as at 97, a pressure gage if such is desired, otherwise, a plug may be threaded into the bore 95 thereby to close off the same.

From the above description it is apparent that the present pumping unit is designed to be manufactured at a low cost for the reason that the entire unit is made up of a plurality of lesser units which may be assembled together by persons having little or no mechanical skill. Fur-

thermore, the present pump design is such that relatively unskilled persons may readily disassemble and assemble this unit for the purpose of inspecting and replacing the various component parts thereof. It is to be understood that the unit broadly comprises a casing 10 having formed therein a pair of spaced chambers 11 and 15 which are connected by means of a bore 14. In order to assemble the various parts of the unit it is only necessary to insert the shaft 19, having the ring 27 thereon, into the rear chamber 15, place the pumping elements over the forward end of the shaft, and then tighten the bolts 26 in place and position the ring 28 and snap 29 over the shaft and against the plate 25. Thus, the main elements of the pump require no elaborate tools for the assembly thereof. The remaining elements of the pump proper, including the oil sealing units and the filter element, may thus be slipped into position and locked within the casing by merely bolting home the two end caps.

The assembly method of the valve mechanism is substantially the same as that of the pump unit for the reason that the removal of the two nuts 77 and 84 of the valve unit will expose all of the internal valve mechanism which may be hand assembled and disassembled in place.

We claim:

1. In a device of the character described having a unitary casing with a front and a rear chamber each formed centrally within a respective one of the opposite end portions thereof, an interior wall portion of said casing separating said two chambers and having a central bore formed therein for connecting said two chambers, an end cap removably secured over each of said chambers, a rotary pump disposed within said front chamber and against said interior wall portion, a fluid delivery conduit formed in said casing and communicating with said front chamber for delivering fluid to said rotary pump, and a fluid discharge conduit disposed within said interior wall portion for conducting fluid under pressure from said pump; the combination therewith of a shaft rotatably mounted within said bore and extending into each of said chambers, one end of said shaft extending through that end cap which covers said rear chamber and the other end being operatively connected with said pump, a fluid seal surrounding said shaft and disposed within said rear chamber adjacent the end cap thereof so as to prevent escape of fluid from said rear chamber past said rear end cap, a thrust ring formed intermediate the ends of said shaft and disposed within said rear chamber so as to prevent endwise movement of said shaft in a first direction, means in the form of a split ring carried upon one end of said shaft and engaging said pump so as to prevent endwise motion of said shaft in a second direction, a spiral groove formed about said shaft and connecting said rear chamber with the high pressure side of said pump so as to provide high-pressure lubrication of said shaft, and a conduit formed within said interior wall portion and connecting said rear chamber with the low pressure side of said pump so as to draw the lubricating fluid from said rear chamber, to relieve said fluid seal from pressure of said fluid.
